UNITED STATES PATENT OFFICE.

WILHELM VON PITTLER, OF LEIPSIC, GERMANY.

STEAM-ENGINE.

SPECIFICATION forming part of Letters Patent No. 251,144, dated December 20, 1881.

Application filed April 18, 1881. (No model.) Patented in Germany February 12, 1881.

To all whom it may concern:

Be it known that I, WILHELM VON PITTLER, of the city of Leipsic, in the German Empire, have invented new and useful Improvements in Steam-Engines, of which the following is a specification.

My invention relates to steam-engines connected with the steam-generator and operated by superheated high-pressure steam; and my invention consists in the construction of a fire-chamber surrounded by a series of pipes and closed by a plate, to which a heavy-metal (cast-steel) chamber is attached, extending downward into the fire-chamber. A small quantity of water is at each stroke of the engine injected into the surrounding pipes by means of a suitable pump, the discharge or supply valve of which is regulated by a suitable governor. The thus-injected water is converted into steam in these heated pipes, and passes then into the heavy-metal chamber, where it is converted into superheated steam before entering the steam-cylinder, which latter is placed into said chamber.

In the accompanying drawings, Figure 1 represents a vertical section of the steam-generator with engine attached. Fig. 2 is a top view of the same, and Fig. 3 is an outside elevation. Similar letters represent similar parts.

The steam-generator consists of a suitable base-plate or frame, E, supporting the grate, bars H, and a top plate, F, between which a number of upright tubes, i, are arranged close to each other and surrounding the grate-bars. One tube is connected with the adjoining tube, above and below the flanges of the frame E and top plate, T, by suitable cap-pieces, J, forming a communication from one tube with the next tube, so that the water from which the steam is to be generated will pass down one tube and upward in the next tube, then downward again in the adjoining tube and upward again in the next, and so on. These cap-pieces J form at the same time slip-joints for the tubes, to allow the same to expand and contract freely. These tubes are placed close to and around the grate-bars H, except in the front, where sufficient space M is left for the arrangement of the necessary fire-door N, and are consequently surrounded on all sides by the flame and gases

of the fire. A suitable casing, P, surrounds the outside of these pipes, and in said casing the fire-door N is arranged.

In the center of the top plate, T, a very heavy metal (preferably cast-steel) chamber, A, is arranged, extending some distance downward into the fire-chamber F, formed by the grate-bars H, pipes i, and top plate, T, as above described. Into this metal chamber A the steam-cylinder C, with its slide-valve K, but without any valve-case, is placed, the piston-rod passing through a suitable stuffing-box in the cover of said chamber A, and connected with the moving parts of the engine, arranged upon the top plate, T, in any suitable manner.

The engine is provided with a suitable feed-pump, B, to supply the generator with water, and the discharge-pipe, n, of said pump is provided with a suitable regulating-valve, m, operated by a governor, R, attached to the engine. The water to be converted into superheated steam is injected, by means of the pump B, into one of the tubes, i—say into i'—and circulates then as water and steam through the series of pipes i, as above described, into the pipe i'', from where it passes through pipe b into the "red-hot" heated metal chamber A, to be converted into superheated steam, surrounding the steam-cylinder C and slide-valve K, and passing then above or below the edge of said slide-valve K, in the usual manner, into the cylinder C, to operate its piston, and through its piston-rod the crank-shaft, in the usual manner. The escape-steam passes through a suitable pipe, G, connected with the exhaust of the cylinder, into the atmosphere, or may be used to heat the water to be injected into the generator.

The slide-valve K is operated in the usual manner by means of an eccentric on the driving-shaft, and the quantity of water to be injected into the pipes i of the generator is regulated by means of the governor R, operating and regulating the valve m, so that the quantity of water injected shall be in proportion to the quantity of steam used in the steam-cylinder.

I am aware that steam-boilers have been constructed with pipes surrounding the fire-chamber, and which said pipes have been filled, either wholly or partially, with a regular and constant

quantity of water to be converted into steam ; and I am likewise aware that the top of a steam-boiler has been constructed with a chamber extending downward into the steam-space of the boiler, and in which said chamber the steam-cylinder, with its appropriate slide-valve, has been placed, and therefore do not claim this arrangement, broadly ; but

What I claim as my invention, and desire to secure by Letters Patent, is—

The steam-generator F, consisting of a suitable fire-place or grate-bars, H, surrounded by pipes i, communicating with each other, top

plate, T, with heavy-metal chamber A, extending downward into the generator F, and pipe b, in combination with the steam-cylinder C and its slide-valve K, inclosed in said chamber A, the feed-pump B, supply-valve m, and governor R, the whole being constructed and arranged to operate substantially in the manner and for the purpose herein described.

WILHELM VON PITTLER.
